UNITED STATES PATENT OFFICE.

BENGT M. W. HANSON AND ARTHUR E. THAYER, OF HARTFORD, CONNECTICUT, ASSIGNEES
TO PRATT & WHITNEY COMPANY, OF HARTFORD, CONNECTICUT, A CORPORATION OF
NEW JERSEY.

FOOT-STOCK.

No. 867,198.

Specification of Letters Patent.

Patented Sept. 24, 1907.

Application filed September 8, 1905. Serial No. 277,558.

To all whom it may concern:

Be it known that we, BENGT M. W. HANSON, a citizen of Sweden, and ARTHUR E. THAYER, a citizen of the United States, both residing at Hartford, in the county of Hartford and State of Connecticut, have jointly invented certain new and useful Improvements in Foot-Stocks, of which the following is a specification.

This invention relates to foot-stocks, generally and more especially to that class of said devices employed with various metal-reducing machines, particularly machines for grinding bars or shafts to true cylindrical form. In this work it is necessary to provide for expansion of the stock due to the generation of heat in the grinding process, and this expansion and consequent elongation takes place although the stock under operation is flooded with water, and unless taken up or compensated for will cause unnecessary binding and consequent friction at the point where the centers engage said stock. In these machines the work is supported at its ends by the centers and is rotated upon them, and consequently a constant, regulable bearing-pressure is necessary in order that the stock may be properly supported and thus held from wobbling or irregular rotative movement.

With the end mentioned in view the principal object of the invention is the provision of means for keeping the spring against which the center-carrying sleeve bears under constant tension, while at the same time permitting of the ready adjustment of said sleeve toward and from the work.

A further object of the invention is the provision of improvements in constructional details of the mechanism for adjusting and for retracting the center.

Other objects of the invention will be hereinafter set forth.

In the accompanying drawings, Figure 1 is a transverse vertical section of the frame of a metal-grinding or reducing-machine, looking toward the inner end of the foot-stock, which appears in elevation. Fig. 2 is a longitudinal vertical section on line 2-2 of Fig. 3; and Fig. 3 is a transverse vertical section on the line of the shaft for actuating the center-carrying sleeve.

Like numerals designate similar parts throughout the several views.

Referring to the drawings, the numeral 1 designates the machine-bed upon ways of which is mounted for sliding movement a carriage 2 carrying the head and foot-stocks. In the present drawings, the head-stock 50 is not shown, for the invention relates solely to the foot-stock and to the parts carried thereby.

Designated by 3 is the improved foot-stock, which is provided with a flat base 4 to fit the truncated top 2'

of the carriage and with overhanging side-pieces 5 which bear against the inclined sides 6 of said carriage. 55 A curved arm 7 projects from the foot-stock and overhangs an extension 2' of the base 2 thereof and said arm is bored to receive a sleeve 8 chambered at one end at 9, and in which chamber is mounted a center 10 having a conical shank 10' and a reduced inner end 10". 60

Upon a reduced extension 7' of the arm 7 is threaded a chambered retaining-cap 11 perforated at its outer end to receive the smooth part 12' of a screw 12, said screw having a reduced extension 12" which bears against the end 10" of the center 10, and carrying on its 65 outer end a knurled manipulating knob 13. At its inner end the sleeve 8 is reduced at 8', and upon this reduced end is fitted one extremity of a helical spring 14. On its inner wall the cap 11 is internally threaded at 15, and this thread is of the same lead as the screw 12 70 for a purpose hereinafter described. Working in the internal thread 15 of the cap is an externally-threaded, circular plug 16 slotted to receive a key 17, said key fitting a longitudinal spline or groove 18 in the screw 12. 75

On the center-carrying sleeve 8 is a rack 19, and in mesh with said rack is a pinion 20 carried by a shaft 21 mounted in a bore 22 of the arm 7. This shaft is provided with a series of collars 21', and it is prevented from longitudinal movement by a screw 23 threaded 80 into the arm, and the point of which fits between two of said collars, as shown in Fig. 3. At its outer end the shaft is journaled in a split-bearing 24, and carries a handle 25, said bearing being clamped upon the shaft by a lever-screw 24' to lock the same and hold the 85 sleeve carrying the center in retracted position when desired. In a projection 26 of the arm 7 is formed a slot 27 for the reception of a tool (not shown) for dressing the grinding-wheels; a thumb-screw 28 serving to clamp said tool in place. 90

Designated by 29 is the usual cross-slide and on this is mounted a head 30 having a bearing 31 for the shaft of the reducing-tool.

A guard 32 for protecting the joints between the foot-stock, carriage and bed is illustrated in Fig. 1, as secured by screws 33 to the extension 2'. For adjustably securing the foot-stock to the carriage any desired means may be employed, and I have shown in Fig. 3 an eccentric shaft 34, mounted in a transverse bore 35 of the stock, and carrying a handle 36. A yoke-rod is fitted at its upper end over the eccentric part of said eccentric-shaft, and the stem of the yoke is threaded to receive a T-nut 37 working in the usual T-slot 38 of the carriage. 95

In the operation of the invention when it is desirable 100 to adjust the center-carrying sleeve 8 this is readily ac-

- complished by turning the rod 12, and as said rod engages the thread for its reception in the sleeve, said sleeve will be advanced or retracted as circumstances may require. When the screw turns the plug 16 turns with it and consequently by engagement with the internal thread 15 of the cap moves longitudinally with relation to the screw, and as the leads of the threads of the screw-plug, sleeve and cap are the same, it follows that no compression of the spring will take place, and 10 that it will always act with constant tension against the end of the sleeve 8, thus always forcing forward the center with sufficient force to insure firmness of support without binding, and without, as is usually the case, unnecessarily crowding the center into its receiving-socket in the end of the work. As the plug is provided with a key fitting in a spline or groove of the screw, said screw is free to move longitudinally through the plug, while turning of the screw advances the sleeve 8 and the plug 16 at the same rate. When it is desirable 20 to throw back the center to insert another piece of work this is rapidly accomplished by grasping the handle 25, and thus actuating the pinion 20, said pinion being, as stated, in mesh with the rack 22 of the sleeve 8. In this rearward movement of the parts the screw 12 slides 25 through the plug 16 and the cap 11, and the spring 14 is of course compressed, but after the insertion of the work the lever 25 is released, and said spring reacts, and hold the center against said work with constant yielding pressure during the entire reducing operation.
- 30 While shown applied to foot-stocks the invention is not limited to any specific center, for it may be employed with other kinds of centers and in turning, grinding and other reducing machines found in various arts.
- 35 Changes may be made in various details of the improvement without departure from the invention, which is not limited to the precise devices shown and described.
- Having thus described our invention, what we claim 40 is—
1. The combination, with a support, of a sleeve movable therein; a center carried by the sleeve; a spring bearing against the sleeve; and means for adjusting the sleeve without affecting the tension of said spring.
  - 15 2. The combination, with a support, of a sleeve mounted in a bore thereof; a center carried by the sleeve; a spring bearing against the sleeve; and means for adjusting said sleeve, and simultaneously with such adjustment keeping the tension of the spring constant.
  - 20 3. The combination, with a support having a bore, of a sleeve mounted in said bore; a center carried by the sleeve; a helical spring bearing against the sleeve; and
- means for adjusting the sleeve and maintaining constant tension of said spring.
4. The combination, with a tubular support, of a sleeve 55 mounted in the bore of said support; a center carried by the sleeve; a spring bearing against said sleeve; an abutment for said spring; means for retracting the sleeve; and means for locking said sleeve in its retracted position.
  5. The combination, with a support, of a center-carrier mounted therein, and having a rack; a shaft; a pinion on said shaft for engaging said rack; means for locking the shaft against movement; and a spring carried by the support, and bearing against the center carrier.
  6. The combination, with a foot-stock, of a center-carrier mounted for sliding movement therein; a spring for actuating said center-carrier in one direction; gearing for actuating said center-carrier in the opposite direction; and means for locking an element of said gearing.
  7. The combination, with a foot-stock having an extension slotted to receive a tool for dressing the reducing-wheel, of a tool-clamp on said extension.
  8. The combination, with a foot-stock having an overhanging arm provided with an extension slotted to receive a tool, of a tool-clamping screw threaded into said extension.
  9. The combination, with a foot-stock having bores, at an angle to each other, of a sleeve mounted in one of said bores, and having a rack; a center carried by the sleeve; a shaft mounted in the other bore; a pinion carried by 80 said shaft, and in mesh with the rack; a split-bearing through which the shaft passes; and a screw for compressing the bearing against said shaft.
  10. The combination, with a stock having a bearing, of a sleeve mounted in said bearing; a cap for the sleeve having an internally-threaded wall; a plug externally-threaded to engage said wall; a key on the plug; a screw passing through the plug, and having a groove to receive said key, said screw engaging the sleeve, and its thread being of the same lead as threads of the plug and cap; 90 a helical spring between the sleeve and plug; and a center carried by the sleeve.
  11. The combination, with a stock having a bearing, of a sleeve in said bearing; a center carried by the sleeve; a screw threaded into the sleeve, and having a longitudinal groove; a hollow internally-threaded cap rigid with the rear end of the bearing; an externally-threaded plug splined to the screw; and a spiral spring between the plug and the end of the sleeve.
  12. The combination, with a center-carrier and its center, of a cap having an internally-threaded wall; a spiral spring bearing against the center-carrier; and threaded devices, each having the same lead of thread for adjusting the center-carrier and the spring in consonance with said carrier, whereby compression of said spring is avoided, 100 and the tension thereof will remain constant.
- In testimony whereof we affix our signatures in presence of two witnesses.
